UNITED STATES PATENT OFFICE

GEORGE H. BIRD AND WILLIAM G. BIRD, OF WILMETTE, ILLINOIS.

ROTARY VALVE FOR HYDROCARBON-ENGINES.

1,183,622.

Specification of Letters Patent.

Patented May 16, 1916.

Application filed April 17, 1912. Serial No. 691,301.

To all whom it may concern:

Be it known that we, GEORGE H. BIRD and WILLIAM G. BIRD, both citizens of the United States, residing at No. 510 Washington avenue, Wilmette, in the county of Cook and State of Illinois, have jointly invented certain new and useful Improvements in Rotary Valves for Hydrocarbon-Engines, of which the following is a specification.

10 This invention relates to gas engines, one of its primary objects being to provide an engine of the multiple-cylinder type with simple, compact and efficient mechanism for controlling the admission of the explosive mixture to the cylinders and the exhaust of the burnt gases therefrom.

More particularly, our invention aims to provide a rotary valve for each cylinder of the engine which will open quickly to admit 20 a maximum amount of explosive mixture to the cylinder at the required time and will cut off quickly when the cylinder has been filled and will also open quickly to permit the escape of burnt gases from the cylinder 25 and remain open a maximum period of time so that the gases may all escape before the admission of the explosive mixture.

Another object is the provision of a large 30 admission and exhaust port which will offer minimum resistance to the admission and discharge of the explosive mixture and burnt gases.

Other objects and advantages of the present invention will be apparent as the same 35 is better understood by reference to the following description when considered in connection with the accompanying drawings illustrating one preferred embodiment thereof.

40 Referring to the drawings—Figure 1 is a side elevation of a gas engine equipped with my invention; Fig. 2 is a fragmentary longitudinal sectional view showing one engine cylinder and its coöperative valve; Fig. 45 3 is a horizontal sectional view taken on the line 3—3 of Fig. 2; Figs. 4, 5, 6 and 7 are transverse sectional views taken on the lines 4—4; 5—5; 6—6; and 7—7 of Fig. 2; and Fig. 8 is a view similar to Fig. 2 showing a 50 modified form of valve.

On the drawings, 11 designates the engine cylinders, 12 the crank casing and 13 the drive shaft, all of which may be of any well known or preferred construction.

55 Our invention is particularly adapted for use in connection with multiple-cylinder en-

gines and in the present instance we have shown an engine of the 4-cylinder type although it will be manifest as the invention is better understood that it is applicable to 60 and equally efficient when used in connection with an engine having a greater or less number of cylinders. For cheapness in construction the cylinders are preferably cast *en bloc* and at their upper ends a cylindrical 65 valve casing 14 is formed which extends transversely across a median line of each of the cylinders. This valve casing is also preferably cast *en bloc* with the cylinders as shown but it may be cast independently 70 and bolted, or otherwise secured to the cylinders, if desired. The water jacket 15 which customarily surrounds the cylinders is extended upwardly to surround the valve casing and the water is discharged from the 75 top of the jacket through a suitable pipe 16. Each cylinder is equipped with a piston 17 and a spark plug or plugs 18 in the usual manner.

Communication is established between 80 each cylinder and the valve casing 14 through elongated ports 19 formed in the ends of the cylinders and in order that a minimum amount of resistance may be offered to the passage of the explosive mixture and the burnt gases through these ports 85 they are made comparatively large in size and are elongated to extend substantially across the tops of the cylinders on a diametrical line. Within the valve casing 90 there is rotatably mounted a plurality of co-axially disposed valves 21, each being arranged in coöperative relation with a cylinder of the engine. These valves are rigidly secured together at their ends and prefer- 95 ably, for cheapness in manufacture and to insure against relative annular displacement, they are cast integrally as a single unit or member and may be positioned by inserting them into one end of the casing 100 and may all be driven simultaneously and synchronously from a single driving mechanism.

The valves are all substantially identical in construction and proportion, consequently a detail description of one of the valves will be sufficient for an understanding of the present invention. The valve casing 14 is provided with a lateral port between the adjacent valves, the alternate 110 ports being connected with an explosive mixture supply 22 and an exhaust pipe 23,

respectively, through suitable branches. It will be apparent, therefore, that the valves are arranged with their supply and exhaust ends in alternation, *i. e.*, the supply ends of 5 adjacent valves are disposed next to each other and the delivery ends of adjacent valves are disposed next to each other so that each branch of the supply pipe 22 supplies explosive mixture to two valves and 10 the central branch of the exhaust pipe 23 receives the exhaust from two valves. The exhaust from the end valves in each instance is received by an individual branch. Obviously, this arrangement of the valves 15 might be reversed so that the supply ends of the valves would be located at the ends of the valve casing, in which instance, however, the exhaust ends would still be arranged in alternation with the supply ends, 20 as previously indicated.

Each valve comprises a cylindrical portion 24 which is contracted at the ends of the valve to form shaft portions 25 connecting adjacent valves, a circular space or 25 chamber being thereby provided at the ends of the valves and around the shaft portions 25 communicating with the supply and exhaust ports of the valve casing.

Assuming that the valve shown in Figs. 30 2 and 3 is the second valve from the left-hand end shown in Fig. 1, the port 26 will communicate with the last branch of the supply pipe 22 and the port 27 will communicate with the central branch of the 35 exhaust pipe 23. The left-hand end of the valve shown in Figs. 2 and 3 is, therefore, the supply end and the right-hand end is the exhaust end. The interior of the cylindrical portion of the valve 24 is divided 40 longitudinally by curved partition walls into a supply chamber 28 and an exhaust chamber 29. The supply chamber is supplied with gas from a port 26 through the ports 31 formed in the web at the end of the 45 chamber and the burnt gases are discharged from the exhaust chamber to the port 27 through the ports 32 at the opposite end of the valve. The peripheral walls of the cylindrical valve are provided with a pair 50 of intake ports 33 and 34 and a pair of exhaust ports 35 and 36. The ports 33 and 34 are wider than the port 19 so that the port 19 will be uncovered very quickly and will remain open and wide open for an appreciable length of time to permit the cylinder to fill with gas and will then be closed quickly at the required instant. The ports 55 35 and 36 are also wider than the port 19 and are of greater width than the ports 33 and 34. This construction permits the port 19 to be quickly uncovered at the exhaust period and enables it to remain open long enough for the burnt gases to escape, the exhaust chamber being cut off from the 60 cylinder practically simultaneously with the 65 cylinder practically simultaneously with the

admission of the explosive mixture from the port 33 or 34, as the case may be. It will be observed that the ports 33 and 34 are located rearwardly of the exhaust ports 35 and 36 a distance substantially equal to the 70 width of the port 19, thus enabling the admission to the cylinder to take place immediately after the exhaust is cut off when the valve is rotating in a clockwise direction, viewing Figs. 4 to 7, inclusive. 75

The partition walls between the supply and exhaust chambers terminate at opposite ends of the cylinder in the peripheral walls of the valve. The walls 38 and 39, viewing Fig. 2, extend inwardly from the supply 80 end of the valve and unite at 41 practically in the center of the valve. The wall 38, which is of curved formation as shown, forms a deflector over the port 36 at the closed end of the exhaust chamber and the 85 wall 39 forms a similar deflector over the port 35 so that the exhaust gases from the engine cylinder are deflected toward the open discharge end of the valve where they escape through the ports 32. The walls 42 90 and 43 curve inwardly from the exhaust end of the cylinder and also unite at 41 in the center of the cylinder so that the wall 42 forms a curved deflector over the port 34 at the closed end of the supply chamber 95 and the wall 43 forms a similar deflector over the port 33. It will thus be observed that the explosive mixture delivered to the open end of the supply chamber is deflected by the walls 42 and 43 into the cylinder 100 through the port 19 and that the exhaust gases from the cylinder are deflected by the walls 38 or 39 toward the exhaust end of the valve.

The supply chamber and the exhaust 105 chamber are of substantially equal length, the supply chamber merging from a circular shape at the open end of the valve into two gradually diminishing branches or pockets over the ports 33 and 34 while the exhaust chamber merges from a substantially circular opening at the discharge end of the valve into a pair of gradually diminishing pockets over the exhaust ports 35 and 36. The full length of the valve is thereby 110 utilized for both supply and exhaust purposes with the result that the port 19 in the cylinder may be of maximum length to offer the minimum resistance to the passage of the gases therethrough. In actual practice 115 the port 19 is preferably made of a length substantially equal to the length of the diameter of the cylinder. 120

In Fig. 8 a slightly different construction 125 is shown in which the valve ends, instead of being reduced to form a solid shaft section between the valves, are extended in cylindrical form, the several valves being made in one continuous cylinder. For purposes of admission and exhaust the cylinder 130

drical portions between the valves are provided with a plurality of elongated ports 26' and 27' adapted to register at the proper times upon rotation of the valves with the 5 inlet and outlet ports 26 and 27, respectively.

The valve described is designed to operate on a 4-cylinder engine and makes one complete revolution to two complete cycles of 10 the engine, or, in other words, four revolutions of the engine shaft. The end of the valve shaft is preferably equipped with a sprocket wheel 44 alined with a driving sprocket wheel 45 on the engine shaft, a 15 sprocket chain 46 being trained over the alined wheels to rotate the valves at the desired speed. The timing of the valves and the position and size of the various ports may be varied considerably and the 20 valves may be constructed to rotate once to two, four, six, eight, or any other desired number of revolutions of the engine shaft. The valves may be made tapering in form instead of uniform diameter from end to 25 end, if preferred, in which instance the valve casing would be correspondingly tapered, and preferably made in sections to permit the valves to be positioned therein. Any suitable provision may be made 30 for furnishing the valves with an adequate supply of lubricant.

It will be understood that the structural details shown and described are capable of considerable variation and modification 35 within the scope of our invention.

We claim:

1. In a gas engine, the combination of a valve casing provided with a longitudinally-extending port through which communication 40 may be established with an engine cylinder, and a cylindrical valve rotatably mounted in said casing, said valve being divided by partition walls into an inlet chamber and an exhaust chamber and being 45 provided with ports adapted to register with the port in said casing, the sides of said ports in the valve converging toward the casing and the sides of the port in the casing diverging from the valve.
- 50 2. In a gas engine, the combination of a plurality of cylinders, a cylindrical valve casing mounted on said cylinders, diametrically disposed ports in the ends of said cylinders communicating with said valve casing

and of a length substantially equal to the 55 diameter of said cylinders, and a plurality of coaxially disposed integrally formed valves rotatably mounted in said casing, each of said valves being divided by partition walls formed integrally therewith 60 into inlet and exhaust chambers, the corresponding chambers of adjacent valves being disposed end to end and having openings communicating with a common chamber 65 therebetween.

3. In a gas engine, the combination of a plurality of cylinders, a cylindrical valve casing mounted on said cylinders, a valve member rotatably mounted in said casing and provided opposite each cylinder with 70 an integrally formed partition wall dividing said valve member into exhaust and inlet chambers, the portions of the valve member intermediate adjacent cylinders being reduced 75 in cross-sectional area to provide exhaust and inlet chambers between the casing and valve member, and separate ports providing communication between each of said first-mentioned exhaust and inlet chambers and a corresponding adjacent chamber between 80 the casing and the valve member.

4. In a gas engine, the combination of a plurality of cylinders, a valve casing disposed adjacent an end of said cylinders, a diametrically disposed port in the end of 85 each of said cylinders communicating with said valve casing and of a length substantially equal to the diameter of the engine cylinder, a valve member rotatably mounted in said casing, said valve member being provided opposite each cylinder with integrally formed partition walls dividing said member into internal exhaust and inlet chambers, the portions of the valve member between 90 said cylinders being reduced intermediate adjacent cylinders to provide exhaust and inlet chambers externally of the valve member, the last mentioned exhaust and inlet chambers being alternately arranged, and separate ports connecting each 95 100 of the internal exhaust and inlet chambers with an external exhaust or inlet chamber.
